F. J. LIESKE

LAMP SHADE SUPPORT

Filed March 17, 1922

INVENTOR.

Frank J. Lieske

Charles E. Hines
ATTORNEY.

UNITED STATES PATENT OFFICE.

FRANK J. LIESKE, OF DETROIT, MICHIGAN.

LAMP-SHADE SUPPORT.

Application filed March 17, 1922. Serial No. 544,532.

To all whom it may concern:

Be it known that I, FRANK J. LIESKE, a citizen of the United States, residing at Detroit, county of Wayne, State of Michigan, have invented a certain new and useful Improvement in Lamp-Shade Supports, and declare the following to be a full, clear, and exact description of the same, such as will enable others skilled in the art to which it pertains to make and use the same, reference being had to the accompanying drawings, which form a part of this specification.

This invention relates to lamp shade supports and the object of the invention is to provide a lamp shade support which may be easily connected to the usual electric light socket, a cover being also provided for the electric light socket which is utilizable in combination with the lamp shade support. A further object of the invention is to provide a means for supporting a lamp shade on the usual electric light socket so that the shade may be easily secured to or removed from the socket quickly and without difficulty. Another object of the invention is to provide a hood or cover for the electric light socket which also covers the lamp shade support and may be quickly secured to or removed from the socket. A further object of the invention is to provide a pair of threaded members adapted to be easily secured to the exterior of the socket and a pair of interthreading members which are threaded together to clamp the lampshade therebetween, the inner of said interthreaded members being threaded onto the outer threaded member secured to the electric light socket. Another object of the invention is to provide an alternative form of device comprising an electric socket having threads formed on the lower end thereof onto which the interthreading members for supporting the lamp shade may be threaded. These objects and the several novel features of the invention are hereinafter more fully described and claimed and the preferred form of construction by which these objects are attained is shown in the accompanying drawings in which—

Fig. 1 is a section through the lamp shade and support embodying my invention.

Fig. 2 is a similar section through a lamp shade and support showing the cover for the socket.

Fig. 3 is a view of the lower end of the

socket showing the manner of securing the two threaded members thereto.

Fig. 4 is a perspective view of the interthreaded members adapted to be secured to the socket. 60

Fig. 5 is a perspective view of the outer threaded member adapted to be secured to the lower end of the lamp socket.

Fig. 6 is a perspective view of the interthreaded members adapted to be clamped to 65 the lamp shade.

Fig. 7 is a section therethrough.

Fig. 8 is a section through the lamp shade and support showing an alternative type of construction. 70

Fig. 1 shows an electric lamp socket 1 of the usual construction provided with a key 4 for operating the same. The socket shell 1 is provided with a threaded portion on the interior into which the incandescent bulb 5 75 may be threaded and the socket shell 1 is provided with a circumferential bead or rib 2, as shown in Figs. 1 and 2. As shown in Figs. 3 and 4 a threaded sheet metal member 7 is provided having two beads 8 and 9 80 so the bead 8 being adapted to be slipped over the bead 2 of the socket and the bead 9 being knurled for a purpose hereinafter described. This member 7 is provided with a series of slots 10 so that the beads 8 and 9 85 may be sprung out to engage over the bead 2. At this time a threaded member 12 is threaded over the member 7 as shown in Fig. 3 and the member 12 is provided with a knurled bead 13 for turning the same. The 90 threading of the member 12 on the member 7 draws the bead 8 of the member 7 into tight engagement with the bead 2 thus securing the threaded members 7 and 12 to the socket, the member 7 being held from turning by 95 gripping the knurled bead 9 while the member 12 is threaded thereon by means of the knurled bead 13. The lamp shade 6 is usually formed of glass and is provided with a return bent flange 25 at the upper end which 100 is usually adapted for securing the shade in the normal type of holder. A member 15 is provided as shown in Figs. 1, 6 and 7 having a series of apertures 18 therein to allow heat to escape from the lamp shade and the 105 flange 16 of the member 15 is provided with a depending flange 17 adapted to engage over the flange 25 of the lamp shade as shown in Fig. 1, the member 15 being of sheet metal and provided with threads as shown. 110

A sheet metal member 19 is provided with apertures 22 therethrough for the escape of heat from the lamp shade and the member 19 is provided with an annular shoulder 20 terminating in an outwardly extending flange 21 adapted to engage against the shoulder 23 of the lamp shade as shown in Fig. 1, the member 19 being made of a diameter to fit any of the standard lamp shades. The member 19 is provided with a central cylindrical threaded portion formed of sheet metal and adapted to be threaded over the threaded portion of the member 15 as shown in Figs. 1, 2 and 7. By threading these members 15 and 19 together the lamp shade is bindingly secured between the flange 16 of the member 15 and the flange 21 of the member 19. The threaded member 15 is also internally threaded and when the lamp shade and members 15 and 19 are assembled together as shown the member 15 is threaded onto the member 12 which is secured to the electric light socket, the knurled bead 13 of the member 12 limiting the threading of the interthreaded members 15 and 19 thereon. By means of the apertures 18 and 22 of the members 15 and 19 the heat from the bulb 5 may pass upwardly through the space 24 about the electric light socket and thence outwardly thereby preventing accumulation of heat within the lamp shade. By the construction shown a solid support is provided for the lamp shade on the socket and the lamp shade may be easily removed from the socket 14, and, should the shade become broken the interthreading members 15 and 19 may be unthreaded to allow the support to be secured to a new lamp shade.

In Fig. 2 a cover 27 for the socket is shown having a slot 28 which is moved over the key 4 of the socket and the ring 33 may be unthreaded from the upper end of the socket and inserted through the aperture 34 of the cover 27 and threaded back in place to bindingly secure the cover to the socket. The cover at the upper end is provided with a flat raised portion 29 provided with a series of apertures 30 therein so that heat may pass upwardly from the lamp shade support through the space 35 about the socket and thence outwardly through the apertures 30. At the lower edge the member 27 is provided with a flange 31 having a beaded edge 32, the said member 27 covering the electric light socket and the portion of the lamp shade support on the exterior of the shade. By using this cover 27 the socket and lamp shade support may be made of the cheapest metal obtainable and need not be finished as the parts are hidden from view by the cover which is the only part that needs finishing.

An alternative form of construction is

shown in Fig. 8 in which the lamp shade 6 and interthreading members 15 and 19 clamped thereto are utilized. In this case the threaded members 7 and 12 are dispensed with and the lower end of the socket 1 is provided with threads 3 formed therein and a circumferential bead 2 is provided immediately above the threads 3 to limit the threading of the interthreaded members 15 and 19 thereon. This construction is somewhat cheaper than that shown in Fig. 1 and at the same time has all the advantages thereof. With this device the interthreading members 15 and 19 are threaded together to engage the lamp shade and the threaded member 15 is threaded onto the threads 3 and shown in Fig. 8.

From the foregoing description it becomes evident that the device is very simple and efficient in operation, will rigidly support a lamp shade, is of strong construction and low manufacturing cost and provides a device which accomplishes the objects described.

Having thus fully described my invention, its utility and mode of operation, what I claim and desire to secure by Letters Patent of the United States is—

1. The combination with an electric light socket having a circumferential bead, of a threaded sheet metal member having a bead at the upper edge and adapted to be sprung over the bead of the socket, a second threaded member for contracting and maintaining the first member on the socket, said second member having a knurled bead providing a shoulder at the upper end, an annular member threaded on said second member seating against the bead and having a lateral flange and a peripheral depending flange, and an additional annular member threaded on the last named annular member and having a lateral flange, the said flanges providing a means for supporting a lamp shade.

2. The combination with an electric light socket, of a threaded member secured thereon and provided with a lateral flange and a peripheral depending flange substantially at a right angle thereto, a second member having a lateral flange of substantially the same diameter as the depending flange, and being in threaded relation with the first member, and a lamp shade having the upper end fitting within the peripheral flange of the first member and having a shoulder engaged on the interior by the flange of the second member, the two members together providing the sole support for the shade.

In testimony whereof, I sign this specification.

FRANK J. LIESKE.
